MANDREL

Thomas L. Hughes, Youngstown, Ohio, and Albert E. Twist, Jr., Rutherford, N. J., assignors to Raymond Concrete Pile Company, New York, N. Y., a Corporation of New Jersey

Application October 2, 1931. Serial No. 566,400

35 Claims. (Cl. 153—69)

This invention comprises improvements in mandrels adapted to engage the interior walls of thin annular shells for supporting the shells while various operations are performed thereon.

5 The invention has particular utility in connection with thin metal shells used in the formation of concrete piles; and for the purpose of illustration of the invention, it is described as incorporated in a machine for corrugating pile shells. 10 Such a machine is shown in Patent No. 1,659,166 issued Feb. 14, 1928, to F. A. Schroeder.

That machine has a three-leaf mandrel with means for moving the leaves radially outwardly to engage the shell and radially inwardly to release the shell. One difficulty encountered in the operation of that machine is due to the fact that the leaves, while in expanded position, do not contact along their adjacent edges and therefore while the mandrel is in operative position its 15 surface is broken by gaps between the leaves and the corrugating tools tend to push the metal of the shell into those gaps, thus impairing the smoothness of the machining operation and of the product itself.

20 25 The leaves can be retracted from the shell only until the edges of the leaves contact with each other at home position. The further they move outwardly the larger the gaps become. If the amount of radial travel is held down in order to 30 reduce the gaps to a minimum while the mandrel is expanded, then the diameter of the mandrel at home position is not reduced sufficiently to permit easy removal of the corrugated shell, i. e., the corrugations of the shell do not clear 35 the corrugations of the mandrel, and it is necessary to unscrew the shells from the mandrel even though the shells be tapered. The unscrewing operation, of course, requires much more time than would be the case if the shell could be lifted 40 off the mandrel without unscrewing.

45 Objects of the present invention are to overcome the above difficulties by providing an expandable mandrel having no gaps between leaves while the leaves are in operative position, and having leaves sufficiently retractable to permit lifting the corrugated shell off the mandrel without any unscrewing being required.

Further and other objects and advantages will be apparent from the specification and claims, 50 and from the accompanying drawings which illustrate what is now considered the preferred embodiment of the invention.

55 Fig. 1 shows the lower portion of the machine, partly in section, during the process of corrugating a shell.

Fig. 2 is a cross-section showing the mandrel expanded into the shell.

Fig. 3 is a cross-section on line 3—3 of Fig. 2 showing the mandrel collapsed.

Fig. 8 is a cross-section on line 8—8 of Fig. 7. 65

Fig. 9 is a cross-section on line 9—9 of Fig. 7, but with the mandrel collapsed.

Fig. 10 is a cross-section on line 10—10 of Fig. 7.

Fig. 11 is a cross-section on line 11—11 of Fig. 5. 70

Supported for rotation in base 20 (Fig. 1) is a hollow vertical shaft 22 on the upper end of which is carried a chuck 24 upon which is mounted the collapsible mandrel 26. The chuck and 75 mandrel will be later described in detail.

Power is supplied to the machine by shaft 28 and pinion 30 which engages gear 32 fastened on shaft 22. Also fastened on shaft 22 is gear 34, which, through pinions 36 and suitable transmission gears 38, 40, 42, rotate vertical shafts 44 to transverse carriages 46, 46 along guide-ways 48, 48. Supported in each carriage 46 is a corrugating roll 50.

Vertical columns 52 at the rear of the machine 85 support an upper framework, not shown, which in turn supports the upper ends of ways 48, and carries a bearing 54 for engaging the upper end of the mandrel.

The mandrel is helically corrugated through- 90 out its length, and is collapsible, as will be explained. In operation, the mandrel is first collapsed; then the shell 56 to be corrugated is slipped over the mandrel; the mandrel is then expanded; the machine is then set in motion 95 whereby the mandrel and shell are slowly rotated while rollers 50 press the shell into the corrugations of the mandrel; and finally the mandrel is collapsed and the corrugated shell removed.

100 The improvements covered by the present invention pertain particularly to the mandrel and chuck, the mandrel details being shown in Figs. 2, 3, 4, 5, 6 and 11, while the chuck details are in Figs. 7, 8, 9 and 10.

The mandrel has four sectors instead of three sectors as in former practice. There are two diametrically opposed long (measured circumferentially) sectors 58, 58, and two diametrically opposed short sectors 60, 60. Each sector 58 110

stands upright on a chuck plate 62 which is slidably radially in guides 64 in chuck 24, while each sector 60 is similarly mounted on a plate 66 slidably radially in guides 68. Sectors 58 and 60 have flanged bases 70 and 72 respectively attached by bolts 74 to chuck plates 62 and 66.

On the under sides of chuck plates 62 and 66 are bosses 76 and 78 supporting downwardly projecting studs 80 and 82 respectively.

10 On the lower ends of studs 80 are follower rollers 84 adapted to roll in cam slots 86 cut in cam plate 88, while on the lower ends of studs 82 are follower blocks 90 adapted to slide in cam slots 92, also cut in the cam plate.

15 Slots 86 and 92 cause radial movements of mandrel sectors 58 and 60 respectively whenever the chuck is rotated relatively to the cam plate. Referring to Fig. 8, pins 80 and 82 are shown in this outer position with the mandrel fully expanded. It will be noted that the outer ends of slots 86 are concentric with the circumference of the chuck for about half the lengths of the slots, which means that considerable rotation of the chuck from the position shown may occur before 20 pins 80 begin to move inwardly. On the other hand, slots 92 are so shaped that pins 82 begin to move inwardly the instant the chuck begins to turn relatively to the cam plate. This means that pins 82 and sectors 60 have moved radially 25 inwardly for quite a distance before pins 80 and sectors 58 begin to move inwardly, after which the sectors all move inwardly simultaneously.

The mandrel sectors are shown in expanded relationship in Fig. 5. It will be seen that there 30 are no breaks or gaps in the circumference. When the above described collapsing operation takes place, sectors 58 remain stationary until sectors 60 have moved inwardly sufficiently so that edges 94 of sectors 60 are clear of edges 96 of sectors 58, after which all four sectors move inwardly together, the edges 94 of sectors 60 entering into grooves 98 of sectors 58 as shown in Fig. 6. By this apparatus the outer dimensions 35 of the mandrel are decreased to such an extent (Figs. 3 and 6) that the corrugated shell may be lifted off the mandrel without the necessity of unscrewing the shell.

The means for collapsing and expanding the mandrel will now be described.

50 Cam plate 88 is adapted for rotation around hub 102 of chuck body 24, and plate 88 has a depending rim 100, around which is a suitably supported brake band 104, having toggle links 106, 108 operably connected to a piston rod 110 which is arranged to reciprocate through a guide block 112. Surrounding rod 110 is a compression spring 114 which thrusts against nut 116 on rod 110 and reacts against block 112, thus tending to draw the toggle together and thereby apply the brake band to drum 100. On the outer end of rod 110 is a piston 118 in a cylinder 120. When fluid under pressure is admitted to the cylinder, piston 118 moves rod 110 against spring 114 to move the toggle and release the brake.

65 The chuck is keyed to shaft 22 by key 124 and may be rotated in either direction, preferably by reversible motor 122 which drives shaft 28. While the corrugating operation is going on, the brake is kept out of contact with drum 100 by pushing air in cylinder 120. When the corrugating operation is finished and it is desired to collapse the mandrel in order to remove the shell therefrom, the air is released from the cylinder, allowing spring 114 to apply the brake to the rim of cam plate 88 and then the mandrel is rotated by means

of the motor in such direction relatively to the stationary cam plate as to cause slots 86 and 92 to collapse the mandrel as described above.

The corrugated shell is then removed and the next shell to be corrugated is placed on the mandrel. Then, with the cam plate still stationary, the mandrel is turned in the reverse direction, whereupon cam slots 86 and 92 will expand the mandrel again into operative position. Then air is admitted into cylinder 120 again to release the brake and allow the cam plate to rotate with the mandrel while the corrugating operation is taking place, after which the collapsing and expanding operations will again be carried out.

90 In order to aid the mandrel sectors in resisting the radial pressure of the corrugating wheels, reinforcing devices are provided at spaced intervals in the mandrel. These devices comprise collars 125 fastened to a vertical shaft 126, sliding freely through shaft 22, and each having a pair of arms 128 adapted to reinforce sectors 58 and a pair of arms 130 to reinforce sectors 60. Each arm 128 and 130 is equipped with a hardened plate 132 (Fig. 11) adapted to contact with a hardened plate 134, fastened to a sector. Plates 100 134 slope upwardly and outwardly so there is a certain amount of wedging action between plates 132 and 134. Shaft 126 is vertically movable by air cylinder 136 in the base of the machine. While corrugating is being done, air pressure is maintained in the top of cylinder 136 to draw the reinforcing arms down into their reinforcing positions.

105 On the upper end of shaft 126 is a disc 138 which can drop between ears 140 on the tops of the sectors only when the mandrel is fully expanded, thus providing an indicator to prevent operation of the machine until the mandrel sectors are in proper position. When the mandrel is to be collapsed, pressure in the lower end of cylinder 136 115 serves to raise shaft 126 with collars 125 and disc 138 out of engagement with the mandrel sectors.

The mandrel and chuck are supported for rotation by ball bearing 142 on frame 20.

120 On top of the mandrel sectors and surrounding ears 140 is a safety ring 144 which serves to prevent the sectors flying apart at their upper ends due to centrifugal force, should the mandrel be inadvertently rotated before upper bearing 54 is 125 in operative position.

130 It is to be understood that the invention is not limited to the specific embodiment herein illustrated and described, but may be used in other ways without departure from its spirit as defined by the following claims.

We claim:

1. A mandrel comprising a plurality of sectors and means comprising a chuck for moving said sectors relatively to each other whereby the mandrel may be expanded or collapsed, the edges of each sector being in contact with the edges of the adjacent sector when said sectors are in expanded position.

2. A mandrel comprising a plurality of sectors having their adjacent edges in contact with each other, in combination with means comprising a chuck for moving said sectors relatively to each other whereby the radial dimensions of the mandrel are decreased.

3. A mandrel comprising a plurality of sectors having their adjacent edges in contact with each other, in combination with means comprising a chuck for moving said sectors relatively to each other whereby the radial dimensions of the mandrel are decreased, said chuck being effective.

to restore the sectors to their original positions.

4. A mandrel comprising a plurality of sectors in combination with means for first moving some of said sectors inwardly and then moving the other sectors inwardly whereby the radial dimensions of the mandrel are decreased.

5. A mandrel comprising a plurality of sectors in combination with means for first moving some of said sectors inwardly and then moving the other sectors inwardly whereby the radial dimensions of the mandrel are decreased, and means for restoring the sectors to their original positions.

6. A mandrel comprising a plurality of sectors in combination with means for first moving some of said sectors inwardly and then moving all the sectors simultaneously inwardly whereby the radial dimensions of the mandrel are decreased.

7. A mandrel comprising a plurality of sectors in combination with means for first moving some of said sectors inwardly and then moving all the sectors simultaneously inwardly whereby the radial dimensions of the mandrel are decreased, and means for restoring the sectors to their original positions.

8. A mandrel comprising a plurality of sectors in combination with a chuck operable to first move some of said sectors inwardly and to then move the other sectors inwardly whereby the radial dimensions of the mandrel are decreased.

9. A mandrel comprising a plurality of sectors in combination with a chuck operable to first move some of said sectors inwardly and to then move all the sectors simultaneously inwardly whereby the radial dimensions of the mandrel are decreased.

10. A mandrel comprising a plurality of sectors in combination with a chuck operable to first move some of said sectors inwardly and to then move all the sectors simultaneously inwardly whereby the radial dimensions of the mandrel are decreased, and means for restoring the sectors to their original positions.

11. A mandrel comprising four sectors arranged in two diametrically opposed similar pairs, in combination with means for first moving one of said pairs of sectors inwardly and afterwards moving the other of said pairs of sectors inwardly, for the purpose set forth.

12. A mandrel comprising four sectors arranged in two diametrically opposed similar pairs, in combination with means for first moving one of said pairs of sectors inwardly and afterwards moving the other of said pairs of sectors inwardly, for the purpose set forth, and means for restoring said pairs of sectors to their original positions.

13. A mandrel comprising four sectors arranged in two diametrically opposed similar pairs, in combination with means for first moving one of said pairs of sectors inwardly and afterwards moving both pairs of sectors inwardly, for the purpose set forth.

14. A mandrel comprising four sectors arranged in two diametrically opposed similar pairs, in combination with means for first moving one of said pairs of sectors inwardly and afterwards moving both pairs of sectors inwardly, for the purpose set forth, and means for restoring said pairs of sectors to their original positions.

15. A mandrel comprising four sectors arranged in two diametrically opposed similar pairs, in combination with means comprising a chuck for first moving one of the pairs of sectors

inwardly and afterwards moving the other of said pairs of sectors inwardly, for the purpose set forth.

16. A mandrel comprising four sectors arranged in two diametrically opposed similar pairs, in combination with means comprising a chuck for first moving one of the pairs of sectors inwardly and afterwards moving the other of said pairs of sectors inwardly, for the purpose set forth, said chuck being effective to restore said pairs of sectors to their original positions.

17. A mandrel comprising four sectors arranged in two diametrically opposed similar pairs, in combination with means comprising a chuck for first moving one of said pairs of sectors inwardly and afterwards moving both pairs of sectors inwardly, for the purpose set forth.

18. A mandrel comprising four sectors arranged in two diametrically opposed similar pairs, in combination with means comprising a chuck for first moving one of said pairs of sectors inwardly and afterwards moving both pairs of sectors inwardly, for the purpose set forth, said chuck being effective to restore said pairs of sectors to their original positions.

19. A chuck for moving the sectors of a collapsible mandrel, comprising a separate member for supporting each of said sectors, in combination with means for first moving certain selected members radially while holding the other members immovable, and afterwards moving the other members radially.

20. A chuck for moving the sectors of a collapsible mandrel, comprising a separate member for supporting each of said sectors, in combination with means for first moving certain selected members radially while holding the other members immovable, and afterwards simultaneously moving all said members radially.

21. A chuck for moving the sectors of a collapsible mandrel, comprising a separate member for supporting each of said sectors, in combination with means comprising cams for first moving certain selected members radially while holding the other members immovable, and afterwards moving the other members radially.

22. A chuck for moving the sectors of a collapsible mandrel, comprising a separate member for supporting each of said sectors, in combination with means comprising cams for first moving certain selected members radially while holding the other members immovable, and afterwards moving the other members radially.

23. A chuck for moving the sectors of a collapsible mandrel, comprising a separate member for supporting each of said sectors in combination with a plate bearing cams adapted to engage said members, and means for causing relative circumferential motion between said members and said plate whereby certain selected members are moved radially while other members are held radially immovable, and finally said other members are also moved radially.

24. A chuck for moving the sectors of a collapsible mandrel, comprising a separate member for supporting each of said sectors in combination with a plate bearing cams adapted to engage said members, and means for causing relative circumferential motion between said members and said plate whereby certain selected members are moved radially while other members are held radially immovable, and finally all said members are moved radially.

25. A chuck for moving the sectors of a collapsible mandrel, comprising a separate member

for supporting each of said sectors, in combination with a plate bearing cams adapted to engage said members, a brake for holding said plate stationary, and means for rotating said members relatively to said plates whereby certain selected members are moved radially while other members are held radially immovable, and finally said other members are also moved radially.

26. A chuck for moving the sectors of a collapsible mandrel, comprising a separate member for supporting each of said sectors, in combination with a plate bearing cams adapted to engage said members, a brake for holding said plate stationary, and means for rotating said members relatively to said plates whereby certain selected members are moved radially while other members are held radially immovable, and finally said other members are also moved radially.

27. A chuck for moving the sectors of a collapsible mandrel, comprising a separate member for supporting each of said sectors in combination with a plate bearing cams adapted to engage said members, a brake, means for actuating said brake to hold said plate stationary, and means for rotating said members relatively to said stationary plate whereby certain selected members are moved radially while other members are held radially immovable, and finally said other members are also moved radially.

28. A chuck for moving the sectors of a collapsible mandrel, comprising a separate member for supporting each of said sectors in combination with a plate bearing cams adapted to engage said members, a brake, means for actuating said brake to hold said plate stationary, and means for rotating said members relatively to said stationary plate whereby certain selected members are moved radially while other members are held radially immovable, and finally all said members are moved radially.

29. The invention set forth in claim 27 in which said brake actuating means comprises a spring for moving said actuating means in one direction and an air cylinder for moving it in the other direction.

30. The invention set forth in claim 28 in which said brake actuating means comprises a spring for moving said actuating means in one direction and an air cylinder for moving it in the other direction.

31. A mandrel comprising a plurality of sectors, means for moving some of said sectors inwardly in successive order, and means co-acting with the aforesaid means for restoring the sectors to their original positions.

32. A mandrel comprising a plurality of sectors, means for moving pairs of said sectors inwardly in succession, and means co-acting with the aforesaid means for restoring the sectors to their original positions.

33. A mandrel comprising a plurality of sectors, means for moving some of said sectors inwardly in successive order, means co-acting with the aforesaid means for restoring the sectors to their original positions, and means for holding the sectors against contraction when in their original positions.

34. A mandrel comprising a plurality of sectors, means for moving some of said sectors inwardly in successive order, means co-acting with the aforesaid means for restoring the sectors to their original positions, and means for rotating said sectors as a unit.

35. A mandrel comprising a plurality of sections, means for moving seriatum certain of said sections partially inwardly and then simultaneously moving all of said sections fully inwardly.
